and
By their Attorney Frank M. Ashley
Frank M. Ashley

UNITED STATES PATENT OFFICE.

HENRY TRUST, OF PARK RIDGE, NEW JERSEY, AND FRANK M. ASHLEY, OF BROOKLYN, NEW YORK; SAID ASHLEY ASSIGNOR TO JOSEPHINE TRUST, OF PARK RIDGE, NEW JERSEY; JOSEPHINE TRUST ADMINISTRATRIX OF SAID HENRY TRUST, DECEASED.

PRESSING AND STRAINING MACHINE.

Application filed December 10, 1919. Serial No. 343,965.

To all whom it may concern:

Be it known that we, HENRY TRUST, a citizen of the United States, and resident of Park Ridge, in the county of Bergen and State of New Jersey, and FRANK M. ASHLEY, a citizen of the United States, and resident of Brooklyn, in the county of Kings and State of New York, have invented certain new and useful Improvements 10 in Pressing and Straining Machines, of which the following is a specification.

Our invention relates to machines for use in restaurants and kitchens for preparing food, etc. The object of our invention is 15 to provide a machine suitable for mashing and comminuting potatoes and other such vegetables and for straining soups and expressing fruit juices.

Referring to the drawings which form a 20 part hereof:

Figure 1 is a vertical sectional view of a machine embodying our invention.

Figure 2 is a plan view.

A indicates the base of the machine provided with a cylindrical upper part A' having an annular groove A² in which is seated below the top thereof an outwardly extending beaded edge B' of the receptacle B. The base A is provided with an extending portion A³ and is open on the sides to permit a pan to slide under to receive the finished product. The extension A³ makes the machine more stable and also permits a pan of larger diameter being placed 30 under the base. C indicates lugs cast integral with the cylinder portion A' and D is a rod hinged thereto and mounted on a cross rod E. The rod D is provided with a headed end D' which rests in a socket 35 F' formed in the link F. Lugs C'—C' are formed on the cylinder and are used for holding a ring G in position over the bead B' of the receptacle B to prevent the receptacle from being raised when the 40 piston H is operated. The ring G is provided with inwardly extending lugs G'—G' which engage the under side of the lugs C'—C' respectively indicated in dotted lines in Figure 2 and held at its bifurcated portion G² by means of the lever nut G³ which is threaded to fit the bolt E and 45 clamps the lug G² to one of the lugs C

cast on cylinders. The piston H comprises a metal cap H' in which is fitted a wooden block H² having a groove H³ and a sheet metal top H⁴ which is held by spinning the edge H⁶ over the peripheral edge of the top H⁴.

The piston rod I is provided with a cross head I' which extends laterally from each side of said rod and staples J—J respectively, are driven through the top H⁴ into the block H² above the ends I', thus holding the piston rod to the piston and permitting the rod to swing relative to the piston. 60 The construction of the piston is such as to render it light, stiff and strong and cheap to construct. The lever K is connected at one end to the link F in hinged relation as shown in Fig. 1 and to the piston rod 65 coupling L at K'. The lever is provided with an extension K² adapted to slide outward over the end of the lever to increase the leverage.

When the lever is raised to the upper 75 position indicated by the dotted lines K³, it can be moved laterally to swing the piston away from the cylinder A' to permit access to the receptacle B, the link F being constructed to swivel on the head D' of rod so D, as will be readily understood.

The bottom edge of the receptacle B is provided with an inwardly extending bead B² on which is supported a perforated disc M. This disc may be replaced by discs 85 having other forms of perforations, larger or smaller, depending on the article to be mashed or comminuted, etc.

To operate the machine the lever K is raised and swung aside, the materials to be mashed or strained placed in the receptacle B and the piston then placed above them and by means of the lever the piston is forced downward into the cylinder thus mashing and forcing the food through the 90 perforated plate M into a pan placed under the receptacle as will be readily understood.

Having thus described our invention, we claim as new and desire to secure by 100 Letters Patent:

1. A machine comprising a base portion, a receptacle having a beaded top edge from which it is suspended from the top of said

base portion, means fixed to the receptacle and overlying said beaded edge for holding said receptacle in position, a piston, and means connected to said base portion 5 and said piston for reciprocating said piston in said receptacle and for swinging said piston laterally from above the same.

2. A machine comprising a base portion having a cylindrical top with an outwardly 10 extending bead formed thereon and lugs at one side thereof, and a ring having in-

wardly extending lugs adapted to engage said bead and also having a bifurcated depending lug, and means for clamping said bifurcated lug to said lugs on the cylindrical portion. 15

Signed at New York city in the county of New York and State of New York this 3rd day of December A. D. 1919.

HENRY TRUST.
FRANK M. ASHLEY.
